(73) Assignee: **BabyPreferred LLC**, Sacramento, CA (US)

(57) **CLAIM**

The ornamental design for drool pad and bib for child carrier, as shown and described.

(**) Term: **15 Years**

DESCRIPTION

(21) Appl. No.: **29/688,044**

FIG. 1 is a front isometric view of the drool pad and bib for child carrier of the invention shown attached to a child carrier.

(22) Filed: **Apr. 17, 2019**

FIG. 2 is a front isometric view of the drool pad and bib for child carrier of FIG. 1.

(51) LOC (12) Cl. **03-01**

FIG. 3 is a front view of the drool pad and bib for child carrier of FIG. 2.

(52) U.S. Cl.

FIG. 4 is a rear view of the drool pad and bib for child carrier of FIG. 2.

USPC **D3/318**

FIG. 5 is a top view of the drool pad and bib for child carrier of FIG. 2.

(58) **Field of Classification Search**

FIG. 6 is a bottom side view of the drool pad and bib for child carrier of FIG. 2.

USPC D3/213, 318; D2/864
CPC A47D 13/02; A47D 13/025

FIG. 7 is a right side view of the drool pad and bib for child carrier of FIG. 2.

See application file for complete search history.

FIG. 8 is a left side view of the drool pad and bib for child carrier of FIG. 2.

(56) **References Cited**

FIG. 9 is a cross section view through view lines 9-9 of FIG. 1; and, FIG. 10 is a top view of the drool pad and bib of FIG. 2 in their unfolded, flat state.
